SCREEN BLOCK

Thomas J. Stoy, P.O. Box 58, Bigler Road,
Clearfield, Pa.

Filed June 10, 1963, Ser. No. 75,275

Term of patent 3½ years

(Cl. D18—2)

FIG. 1

FIG. 2

FIG. 3

FIG. 4

FIG. 1 is a perspective three-dimensional view of the screen block of this invention;

FIG. 2 is a front elevation of the screen block of FIG. 1;

FIG. 3 is a side elevation of the screen block of FIG. 1; and

FIG. 4 is a bottom view of the screen block of FIG. 1.

I claim:

The ornamental design for a screen block, as shown.
